UNITED STATES PATENT OFFICE.

EDWARD HALE, OF WIGAN, ENGLAND, ASSIGNOR TO JAMES J. McCOMB, OF NEW YORK, N. Y.

METALLIC HOOP.

SPECIFICATION forming part of Letters Patent No. 226,065, dated March 30, 1880.

Application filed December 12, 1879. Patented in England September 19, 1877.

To all whom it may concern:

Be it known that I, EDWARD HALE, of Wigan, in the county of Lancaster, England, have invented a new and useful Improvement in 5 Metallic Hoops, of which the following is a specification.

This invention relates to hoops of iron, steel, or other suitable metal used for the purpose of securing the staves of barrels, casks, and 10 other vessels, and also for baling various elastic materials, and for other purposes.

The ends of metallic hoops when used for the purposes above indicated are usually united or secured together by means of rivets, buckles, 15 links, or other fastenings; and to effect this union they are usually punched, cut, drilled, bent, or twisted in such way as to weaken such ends and render them liable to break under less strain than the body or intermediate part 20 of the hoop would sustain.

It is the object of this invention to remove this liability in metallic hoops to break at their weakened ends by making such ends stronger than the intermediate length of the hoop, 25 which is not subjected to any weakening by the union of the ends; and it consists in a metallic hoop having its ends thicker than its body or intermediate part, and also of the method of making such hoops.

30 The invention is illustrated in the accompanying drawings, in which Figure 1 is a perspective view of the hoop; Fig. 2, a section of a roller provided with a deepened groove, and Fig. 3 a section of a roller having a portion of 35 its circumference cut away.

In these drawings, *a a* represent the thickened ends of a metallic hoop, the body or intermediate part of which is represented by *A*.

40 *B* represents a grooved roller having one of its grooves, *b*, cut away or deepened, as shown at *c*, and *D* represents a plain roller having a portion of its circumference removed or flattened, as shown at *d*.

45 As metallic hoops are more frequently joined by riveting than otherwise, the ends of the hoop shown in Fig. 1 of the drawings are provided with holes for the insertion of rivets.

Metallic hoops are generally made by pass-

ing the metal between heavy rollers, which may be provided with grooves, by which the desired 50 width and thickness is given to the metal, which may then be cut to the desired lengths; or they may be formed from sheets of metal which has been brought to the desired thickness by rolling or otherwise, then stripped into 55 the proper widths, and afterward finished by being passed between plain rollers, and then cut into lengths as required; but heretofore, so far as known, such hoops have been substantially 60 of the same width and of uniform thickness throughout their entire length.

Hoops having their ends thickened or thicker than the part lying between the ends, as provided for by this invention, can be readily and conveniently made by cutting out the grooves 65 in the rollers, as represented by *c* in Fig. 2, so that they will be somewhat deeper throughout a certain part of their circuit around the roll, in order that, as the metal is carried forward by the revolution of the rolls, it will be left 70 thicker at the part where the groove has been deepened. By increasing or diminishing the circumference of the rollers the distances between the thickened parts of the rolled metal will be correspondingly varied, so that by cutting the strips of metal thus formed midway 75 of each thickened part hoops of any required lengths can be provided.

Instead of rolling the metal into strips of the proper width for a single hoop, sheets of 80 metal may be treated by passing them between rollers having a part of their circumference flattened or cut away, as shown in Fig. 3 by the letter *d*, which will operate to leave the sheet of metal thicker for the required space 85 at every revolution of the rollers, and the sheets thus formed can then be cut into hoops, as already described.

It will be seen that the shape and extent of the thickened part of the metal can be varied to 90 suit the various conditions of use to which the hoops may be subjected.

The ends of the hoops should be made enough thicker than the body thereof to compensate for the weakening of such ends by 95 the special mode which may be adopted for

securing them together; and as the extent of this weakening can generally be accurately ascertained, as well as the increased strength arising from additional thickness, the desired compensation can be made.

5 It follows that by this construction a great saving in metal can be made in all cases in which it is necessary to weaken the ends of the hoops, as by punching, cutting, or bending them in order to unite them, and, at the same time, a hoop so made will be lighter and equally strong to resist tensile strain, as if it were of the same thickness throughout its whole length as at its ends.

15 In some instances, as where bales have been loosely bound, and afterward it is desired to compress them and secure them by the use of the same hoops or bands, it is necessary to make a second fastening at some distance from the end of the hoop. In such cases, in order to make such second fastening secure, the hoops may be strengthened at the point where such fastening would come, substantially as at their ends.

25 I am aware that it has been proposed in the manufacture of boilers to thicken the boiler-plates along their riveted edges.

I am also aware that it has been proposed

to form metallic wrappers or envelopes for bales with a number of ribs at proper intervals apart, 30 extending across the metallic envelope at right angles with the edges to be riveted. I claim none of these things.

What is claimed as new is—

1. As a new article of manufacture, the metallic hoop described, having its ends made thicker than its body or part lying between such ends, substantially as and for the purposes described.

2. The method herein described of making 40 blanks for metallic hoops, which consists in passing sheets of metal between rollers having a part of their surface cut away or flattened, as described, whereby the sheets are left thicker at distances, and then dividing the 45 sheets across through the thickened parts and stripping the sections into the desired widths, thus forming blanks for hoops, each of whose ends are thicker than their bodies or parts lying between such thickened ends, substantially as described.

EDWARD HALE.
